COTTON PICKER

Robert S. Curley, Biddeford, and William Shaw, Saco, Maine, assignors, by mesne assignments, to Saco-Lowell Shops, Biddeford, Maine, a corporation of Maine

Application January 23, 1937, Serial No. 121,996

14 Claims. (Cl. 19—89)

A typical cotton picker comprises a beater section, a condenser section adjoining it, and a blower for creating the suction required in the condenser section and producing the flow of air necessary to convey the cotton from the beater to the condenser. In a picker room where a battery of these machines are in operation, a large volume of air is continuously withdrawn from the room and exhausted out of doors. This is undesirable in the winter time and in cold climates because of the loss of heat, and it is objectionable at any time because of the difficulty of controlling the humidity in the picker room under these conditions.

With a view to overcoming these objections it has been proposed to equip the individual pickers with means for recirculating the air utilized in conveying the cotton, and to provide some means for removing the heavier foreign materials picked up and carried along by said air stream. No practical arrangement of this character has ever been devised, so far as we are aware, largely due to the difficulty of cleaning up the air stream sufficiently to prevent the production of a dirty sheet. A further objection to installations of this type has been the inability to control the air properly so that a good sheet would be delivered by the condenser. In other words, this fact of recirculating air in a closed circuit disturbs, in some manner, the uniformity of flow or the proper distribution of the air, with the result that the sheet produced is far less uniform than that made in machines operated in the usual manner.

The present invention deals with these problems, and it aims to devise a thoroughly satisfactory solution for them.

The nature of the invention will be readily understood from the following description when read in connection with the accompanying drawings, and the novel features will be particularly pointed out in the appended claims.

In the drawings,

Figure 1 is a vertical, sectional view, somewhat diagrammatic in character, of a picker unit equipped with an air filtering mechanism constructed in accordance with this invention;

Fig. 1a is a sectional view of a modified filter construction;

Fig. 2 is a sectional view on a larger scale of the filter structure shown in Fig. 1 and the parts immediately associated therewith; and

Fig. 3 is a horizontal, sectional view approximately on the line 3—3, Fig. 2.

Referring first to Fig. 1, the construction there shown comprises a beater 2, condenser cylinders

3—3, a blower 4, and the delivery rolls 5 associated with the condenser to discharge the sheet, all of these parts being constructed, arranged and operated in the well known manner. As usual, the beater, condenser and blower are enclosed in a casing 6 which is equipped with ducts for conducting air from the condenser screens or cylinders 3 to the intake of the blower and with suitable partitions for directing or guiding the flow of air through the dust chamber in the casing along the desired paths. So far as these features are concerned, no change need be made in the prior art constructions. Also, the cotton may be fed to the beater in any suitable manner, the particular arrangement shown consisting simply of a feed table 7 across which a sheet delivered by a previous unit is guided to the feed rolls 8 of the beater.

According to the present invention a filter unit, indicated in general at 10, is installed in some convenient location in the machine, as for example, directly under the feed table 7. As best shown in Figs. 2 and 3, this unit comprises upper and lower, hollow, driven rolls 12 and 13, respectively, of perforated or foraminous construction, and a filter screen 14 in the form of an endless belt stretched over and supported on these rolls. Both rolls extend horizontally across the entire space inside a filter housing or casing 15, and are supported for rotation in bearing elements 30 forming a part of said housing. The ends of these rolls project through the housing and consequently, the spaces inside them are in free communication with the air spaces 16—16 in the casing 6 at opposite ends of the filter casing 15, 35 these spaces 16 communicating directly with, or forming a part of, the dust chamber in the casing 6. Also, the end plates *a* and *b* are cut away, as shown at 19—19, to provide free communication between the air spaces 16 and the space 40 inside the filter screen.

As shown in Fig. 3, the blower 4 draws air from the beater through condenser cylinders 3, the ducts 17—17 in the casing 6 and the pipes 18—18, and discharges it through a conduit 20 which connects the exhaust end of the blower with the lower part of the filter casing 15. This casing is substantially closed except for its intake, the openings 19—19 and those through the opposite ends of the rolls 12 and 13. Consequently, this stream of air is compelled to flow through the filter sheet or screen 14, thence into the chambers 16—16, and from there into the main portion of the dust chamber in the casing 6. While some of this air flows directly through the portion of 55

this screen that partly encircles the rolls 12 and 13, the greater part of it flows through the broad, vertical, flat runs or sheets connecting the two rolls, and thus enters the space between these runs 5 from which it can flow freely through the holes 19-19 in the ends of the casings or through the rolls. The screen 14 may be made of any suitable filtering material, that preferred consisting of a fine woven wire screening, such as the Fourdrinier 10 wire used in paper making machines.

As the air flows through this screen in the manner just described, it deposits most of the solid material carried by it on the outer surface 15 of the screen, thus filtering the air very effectively. At the same time the lint and other solid materials collect on the screen in the form of a layer or fleece. In order to keep this filter in efficient condition, such accumulations must be removed practically continuously from the surface 20 of the screen, and for this purpose two feed rolls 21 are mounted, one above the other, closely adjacent to the surface of the screen 14 where it bears against the lower roll 13. These two rolls 25 are driven continuously in opposite directions at a slow speed, and they serve to remove the fleece from the surface of the screen and feed it away from this surface and into a box or drawer 22 which can be removed from time to time and emptied. Such removal of the accumulated waste 30 material from the surface of the screen would be impeded by the pressure of the air stream against it if it were not for the fact that the casing 15 is provided with a flange 23 extending inwardly to a point where it just clears the upper 35 roll 21, while another flange or shield 24, curved around the lower roll 13, terminates substantially at the periphery of the lower of the rolls 21. Thus these parts reduce the air flow to negligible 40 limits in the region at which the fleece is being removed from the screen.

Any suitable arrangement may be used for driving the filter and the parts associated therewith, the particular construction shown comprising a chain 25, driven by a sprocket wheel on 45 the lower condenser cylinder-shaft 26 and driving a sprocket wheel 27, Figs. 2 and 3, on a shaft 28. This shaft is connected by a sprocket and chain drive with another shaft 30 on which the upper roll 21 is mounted, this roll being geared directly 50 to its companion lower roll, and also driving a gear 31 fast on one end of the lower hollow roll 13.

As above stated, one of the difficulties experienced in operating a picker in which the air is recirculated through a fixed path inside the machine is that the condenser does not deliver as uniform a sheet or web of cotton as it should. Apparently this is due to some fault in air distribution inside the dust chamber. Our investigations indicate that the blower picks up air on 55 its suction side through leaks which are extremely difficult, if not impossible, to stop, and which may, in fact, be desirable, and it discharges this air into the dust chamber where it creates an excessive pressure which seems to be 60 responsible for the difficulty above described. But whatever the correct explanation may be, we have found that this condition can be remedied by providing openings 33-33 through 65 the casing 6 at opposite sides of the dust chamber which afford a limited but substantial interchange of air between the dust chamber and the picker room. In other words, while the greater 70 part of the filter air is returned to the beater 75 and is re-circulated and the entire air stream

used in the machine is guided in a fixed and predetermined circuit, nevertheless a sufficient interchange of air is permitted between the dust chamber and the surrounding atmosphere to maintain the air pressure in the dust chamber always equal to, or balanced by, that of the surrounding atmosphere. This arrangement we find has an extremely important effect in the formation of the sheet, and enables us to control the sheet forming operation as accurately, and to produce as uniform results, as those obtained by the orthodox pickers not equipped to recirculate the air. These equalizing openings 33-33 may either be left entirely open, or may be partially closed with grids, as illustrated in Figs. 2 and

The arrangement above described thus provides for the continuous flow in a complete circuit of the large volume of air required in a picker, while at the same time filtering the greater part of the foreign materials out of the air stream and maintaining the filter screen automatically and continuously in an effective condition. In addition, it provides for that equalization of air pressure inside and outside the machine which is necessary in order to make a good sheet. It will be observed that both runs of the filter screen 14 extend entirely across the space between the plates *a* and *b* and that the broad flat surfaces may be as high as the dimensions of the machine will permit. Consequential this arrangement provides very large air filtering areas. Leakage around the edges of the screen between it and the walls *a* and *b* may be minimized by placing batten strips 37-37 just inside the screen where its margins will bear against said strips, these strips extending vertically from the roll 12 to the roll 13. Hand holes 36-36, normally closed by removable plates, are provided in the machine casing in line with the space inside the filter screen so that an operator can reach into this area if necessary for any purpose. The openings 19-19 through which the air escapes from the inside of the filter screen into the compartments 16-16 of the dust chamber, afford a volume of flow which may be adequate without making the rolls 12 and 13 of foraminous construction, and consequential either, or both, of them may be made solid or of tubular non-perforate form. In fact, it is preferable when the additional air space is not necessary, to make the lower roll 13 of imperforate form since this makes it easier to strip the fleece from the screen 14.

Another form of filter which can be used in place of that shown and has the advantage of presenting a large filtering surface for handling the large volume of air used in pickers, is shown in Fig. 1a. Here several tubular rolls of foraminous construction, illustrated at 40, 41, 42 and 43, are mounted one above the other in peripheral contact with each other, each roll having a covering or peripheral surface consisting of fine mesh screen or its equivalent. All of the rolls are driven slowly in the same direction as they are all mounted in the same general manner as are the rolls 12 and 13 of the construction previously described. Consequently, the air discharged by the blower 4 passes through the surfaces of these rolls into their bores and out in the chambers 16-16, the screening surfaces of the rolls filtering out the coarser solid material carried by the air stream. As above indicated there is sufficient residual fiber in the air stream to form a fleece on the screening surface, and this fleece is transferred from the left-hand side

of the lower roll 40 to the same side of the next roll above it, and so on to the uppermost roll 43. This roll, in turn, transfers its fleece to the right-hand side of the roll 42 which gives it up to the roll 41 and the accumulation on the latter is taken off by the bottommost roll 40. Stripper rolls 21, like those shown in Fig. 2, are associated with the last mentioned roll and serve to remove the fleece from it and deposit it in the dust box 22.

While we have herein shown and described a typical embodiment of our invention, it will be understood that the invention may be embodied in other forms without departing from the spirit 15 or scope thereof. For example, other forms of filters and condensers may be substituted for those shown.

Having thus described our invention, what we desire to claim as new is:

20 1. A cotton picker including a beater, a condenser, a casing enclosing said beater and condenser, and a blower communicating with said condenser and arranged to create suction in it and to produce a flow of air through said beater and through the dust chamber in said casing, in combination with means for conducting the exhaust air from said blower and discharging the same into said chamber, a filter screen through which said means compels said exhaust air to flow, means for supporting and feeding said screen to interpose a broad flat section of the screen continuously across said exhaust air stream, whereby the lint, fiber and foreign materials carried by said stream will be deposited 30 upon said flat section of the screen, and means for removing said deposit from said screen.

2. A cotton picker including a beater, a condenser, a casing enclosing said beater and condenser, a blower communicating with said condenser and arranged to create suction in it and to produce a flow of air through said beater and through the dust chamber in said casing, in combination with a pair of rolls, a filter screen supported on said rolls in the form of a belt, mechanism for revolving one of said rolls and thereby feeding said belt, and means for conducting the exhaust air from said blower through said filter screen and thence back into said dust chamber.

3. A cotton picker including a beater, a condenser, a casing enclosing said beater and condenser, a blower communicating with said condenser and arranged to create suction in it and to produce a flow of air through said beater and through the dust chamber in said casing, in combination with a pair of rolls, a filter screen supported on said rolls in the form of a belt, mechanism for revolving one of said rolls and thereby feeding said belt, and means for conducting the exhaust air from said blower through said filter screen and thence back into said dust chamber, whereby the fiber and dust carried by said exhaust air will collect on said screen in the form of a layer, and power driven means for removing said layer from said screen.

4. A cotton picker including a beater, a condenser, a casing enclosing said beater and condenser, a blower communicating with said condenser and arranged to create suction in it and to produce a flow of air through said beater and through the dust chamber in said casing, in combination with a pair of parallel spaced rolls, a filter screen supported on said rolls in the form of a belt, mechanism for revolving one of said rolls and thereby feeding said belt, one at least 70 of said rolls being hollow and of foraminous con-

struction, a housing in which said rolls and said screen are mounted, means connecting said housing with the exhaust end of said blower whereby the air discharged from said blower will be forced through said screen, through said foraminous rolls, and out the ends thereof, said rolls being mounted for rotation in bearings provided in said housing and said housing being constructed to confine and direct the entire flow of exhaust air through said screen.

5. A cotton picker including a beater, a condenser, a casing enclosing said beater and condenser, a blower communicating with said condenser and arranged to create suction in it and to produce a flow of air through said beater and through the dust chamber in said casing, in combination with a pair of parallel spaced rolls, a filter screen supported on said rolls in the form of a belt, mechanism for revolving one of said rolls and thereby feeding said belt, means for conducting the exhaust air from said blower through said filter screen and thence back into said dust chamber, whereby the fiber and dust carried by said exhaust air will collect on said screen in the form of a layer, a second pair of rolls positioned 25 closely adjacent to said screen where they are operative to take said layer off the screen and feed it away from the latter, and means for reducing the flow of air through said screen in the region of said second pair of rolls, whereby 30 the removal of said layer from the screen by the rolls is facilitated.

6. A cotton picker according to preceding claim 2, in which said means includes a filter housing in which said rolls are mounted where they support said filter belt with its edges in contact with the opposite ends of said housing, the housing being provided with apertures opening into the space inside said belt, whereby air passing through said screen and into said space can 40 escape through said aperture.

7. A cotton picker including a beater, a condenser, a casing enclosing said beater and condenser and a blower communicating with said condenser and arranged to create suction in it and to produce a flow of air through said beater and through the dust chamber in said casing, in combination with means for conducting the exhaust air from said blower and discharging the same into said chamber, and a filter through 50 which said exhaust air is conducted on its way to said chamber, said filter comprising a plurality of filtering rolls mounted to revolve closely adjacent to each other and through which the air flows from the outside to the inside, whereby the accumulated solids collect as a fleece on the outer surfaces of said rolls, and means for revolving them in such directions and in such a relationship to each other that the fleece will be transferred from one roll to another.

8. A cotton picker including a beater, a condenser, a casing enclosing said beater and condenser and a blower communicating with said condenser and arranged to create suction in it and to produce a flow of air through said beater and through the dust chamber in said casing, in combination with means for conducting the exhaust air from said blower and discharging the same into said chamber, a filter through 70 which said exhaust air is conducted on its way to said chamber, said filter including a plurality of hollow rolls through which the air passes from the outside to the inside, and a single mechanism for removing the accumulations of solid 75

material collected on the surfaces of said rolls by the filtering action.

9. A cotton picker comprising a beater, a condenser, an air filter, a casing enclosing said beater, filter and condenser and providing a dust chamber under said beater, a blower connected with said condenser and arranged to create suction in it and thereby to draw air from said dust chamber through said beater and condenser, said filter being located outside said dust chamber, and means connecting said filter with said blower to conduct the air discharged by the blower through said filter and to return the filtered air again to the dust chamber.
10. A cotton picker including a beater, a condenser, a casing enclosing said beater and condenser, a dust chamber in said casing operatively associated with said beater, and a blower communicating with said condenser and arranged to create suction in it and to produce a flow of air through said beater and said dust chamber, in combination with means for conducting the exhaust air from said blower back into said chamber for recirculation through said beater and condenser, a filter including a movable filter surface through which the air stream so created is conducted on its way from said condenser to said chamber, and means for substantially equalizing the air pressure in said chamber with that outside the machine.

11. A cotton picker including a beater, a condenser, a casing enclosing said beater and condenser, a dust chamber in said casing operatively associated with said beater, and a blower communicating with said condenser and arranged to create suction in it and to produce a flow of air through said beater and said dust chamber, in combination with means for conducting the exhaust air from said blower back into said chamber for recirculation through said beater and condenser, and a self-cleaning filter in said casing through which said air stream is conducted on its way from said condenser to said chamber.

12. A cotton picker including a beater, a condenser, a casing enclosing said beater and condenser, a dust chamber in said casing operatively associated with said beater, and a blower communicating with said condenser and arranged to create suction in it and to produce a flow of air

through said beater and said dust chamber, in combination with means for conducting the exhaust air from said blower back into said chamber for recirculation through said beater and condenser, an air filter through which the air stream so created is conducted on its way from said condenser to said chamber, said filter including a movable filter surface through which said air stream flows, and mechanism for moving said surface transversely of the air stream.

13. A cotton picker including a beater, a condenser, a casing enclosing said beater and condenser, a dust chamber in said casing operatively associated with said beater, and a blower communicating with said condenser and arranged to create suction in it and to produce a flow of air through said beater and said dust chamber, in combination with means for conducting the exhaust air from said blower back into said chamber for recirculation through said beater and condenser, an air filter through which the air stream so created is conducted on its way from said condenser to said chamber, said filter including an endless filter surface, mechanism for moving said surface to present different portions thereof in filtering position, and means for removing from said surface material filtered thereby out of the air stream.

14. A cotton picker including a beater, a condenser, a casing enclosing said beater and condenser, a dust chamber in said casing operatively associated with said beater, and a blower communicating with said condenser and arranged to create suction in it and to produce a flow of air through said beater and said dust chamber, in combination with means for conducting the exhaust air from said blower back into said chamber for recirculation through said beater and condenser, an air filter through which the air stream so created is conducted on its way from said condenser to said chamber, said filter including an endless filter surface, mechanism for moving said surface to present different portions thereof in filtering position, and means for substantially equalizing the air pressure in said chamber with that outside the machine.

ROBERT S. CURLEY.
WILLIAM SHAW.
